CATHODE RAY DEFLECTION APPARATUS

Hans Otto Roosenstein and Horst Hewel, Berlin,
Germany, assignors to Telefunken Gesellschaft
für Drahtlose Telegraphie m. b. H., Berlin,
Germany, a corporation of Germany

Application February 12, 1937, Serial No. 125,382
In Germany January 24, 1936

4 Claims. (Cl. 250—157)

Our invention relates to iron core magnetic coils, and more particularly to such a coil for use with cathode rays for deflection purposes.

Heretofore iron core coils had been used for the magnetic deflection apparatus for cathode rays particularly as adapted to use for television purposes or for oscillographic purposes with so-called Braun tubes. These devices heretofore used have in general comprised two coil halves which are disposed on two branches or legs consisting of magnetic material between which is contained the air gap wherein is placed the tube itself, and one or two yokes have been provided such that the magnetic flux closes through an iron path. Arrangements of this type have the disadvantage however that the flux in the air gap of the iron core is rendered sufficiently homogeneous for use only when the iron for the pole pieces has been of comparatively large dimensions. It is, therefore, one of the objects of my invention to provide an iron core magnetic coil in which this disadvantage is obviated.

In general, this invention consists of the provision of one or two main yokes and one or two secondary yokes and, where desirable an air gap is provided in one or both of the secondary yokes. This arrangement allows the provision of a device in which the magnetic flux branched off by the supplementary yokes from the main flux has a course of equal sense and at a line approximately parallel with the line connecting the main pole pieces and the intersecting axis of the tube.

Two embodiments of the invention are illustrated in the drawing, in which

Fig. 1 represents one embodiment of my invention,

Fig. 2 is a cross-sectional view along the line CD of Fig. 1.

Fig. 3 is another embodiment of my invention, and

Fig. 4 is a cross-sectional view along the line CD of Fig. 3.

Referring to Fig. 1, there are provided two coil parts 10 and 11 wound about two legs 12 and 13 respectively, joined to which are two main yokes 14 and 15. On the two legs 12 and 13 are mounted two pole pieces 16 and 17, and the distribution of the lines of force about these pole pieces is clearly shown in the drawing on the right side of center line AB. In accordance with this invention, two secondary yokes are provided comprising the sections 18 to 21. The ends of the two secondary yokes are slotted as shown at 22, and they may be fixed in the correct position with respect to the rest of the yoke mem-

bers by screws 23. The flux closing through yoke 18 and 19, in which is contained an air gap, is shown clearly on the drawing with the result that the field intensity which is usually small at greater distances from center line AB of the flux closing over main yokes 14, 15 is compensated.

The cross-sectional arrangement along the line CD is clearly illustrated in Fig. 2 in which the reference characters indicate the same parts as in Fig. 1.

Referring to Fig. 3, there is shown an embodiment in which only one main yoke 14 is provided, and one sectional yoke 20 and 21 made up in the same fashion as the secondary yokes 15 in Fig. 1 is provided. To the right of center line AB, the non-homogeneity of the flux closing through the legs 12 and 13 and yoke 14 is eliminated by the flux in the air gap of the secondary yoke 20 and 21 in the same manner as explained with reference to Fig. 1. To the left of the center line AB, the stray flux of winding 24 effects in a similar manner at elimination of the non-homogeneity of the deflecting field.

It will be realized, of course, that we may, instead of using air gaps in the secondary yokes, merely constrict the cross-section of the iron and thus perform a similar compensation.

What is claimed is:

1. In combination, a cathode ray tube having means for developing an electron beam, and an apparatus for deflecting said electron beam comprising a main yoke member, a pair of pole pieces which when energized provide an uneven field intensity value along the line of deflection of said electron beam joined to said main yoke member, a supplementary yoke member having an air gap therein joined to said main yoke member, and means for energizing said main yoke member, said supplementary yoke member and said pole pieces, said latter means and said supplementary yoke member each being positioned at a finite distance from said pole pieces whereby the field from said supplementary yoke member and said energizing means substantially compensates for inequalities in field intensity along the line of deflection of said beam.

2. In combination, a cathode ray tube having means for developing an electron beam, and an apparatus for deflecting said electron beam comprising a main yoke member, a plurality of pole members which when energized provides an uneven field intensity along the line of deflection of said electron beam joined to said main yoke member, a pair of adjustable supplementary yoke

- members each having an air gap therein and spaced apart from said pole members a finite distance whereby the flux established by said supplementary yoke members when energized substantially compensates for the inequalities in field intensity along the line of deflection of said beam, and means for energizing said pole members and yoke members.
3. In combination, a cathode ray tube having means for developing an electron beam, and an apparatus for deflecting said electron beam comprising a main yoke member, a plurality of pole members which when energized provides an uneven field intensity along the line of deflection of said electron beam joined to said main yoke member, a pair of adjustable supplementary yoke members each having a constricted section therein and spaced apart from said pole members a finite distance whereby the flux established by said supplementary yoke members when energized substantially compensates for the inequalities in field intensity along the line of deflection

of said beam, and means for energizing said pole members and yoke members.

4. In combination, a cathode ray tube having means for developing an electron beam, and an apparatus for deflecting said electron beam comprising a main yoke member, a pair of pole pieces which when energized provide an uneven field intensity value along the line of deflection of said electron beam joined to said main yoke member, an adjustable supplementary yoke member having an air gap therein joined to said main yoke member, and means for energizing said main yoke member, said supplementary yoke member and said pole pieces, said latter means and said supplementary yoke member each being positioned at a finite distance from said pole pieces whereby the field from said supplementary yoke member and said energizing means substantially compensates for inequalities in field intensity along the line of deflection of said beam. 20
